UNITED STATES PATENT OFFICE.

AUGUST KRAUSE, OF JAMAICA PLAIN, MASSACHUSETTS.

DEVICE FOR OPERATING SLIDING DOORS.

1,032,148.

Specification of Letters Patent.

Patented July 9, 1912.

Application filed March 3, 1909. Serial No. 481,140.

To all whom it may concern:

Be it known that I, AUGUST KRAUSE, of Jamaica Plain, in the county of Suffolk and State of Massachusetts, have invented new

5 and useful Improvements in Devices for Operating Sliding Doors, of which the following is a specification, reference being had to the accompanying drawings, forming part thereof.

10 This invention has reference to improvements in devices for operating center opening sliding doors.

One object of the invention is to so construct an operating device of this nature 15 that, of a pair of doors mounted to slide in opposite directions one of said doors may be automatically operated by the movement of the other of said doors.

Another object of the invention is to so 20 construct a pair of sliding doors that upon the sliding of one of said doors the other door is caused to slide in the opposite direction and said connection may be engaged to prevent the movement of the doors.

25 The invention consists in such peculiar features of construction and combination of parts as shall hereinafter be more fully described and pointed out in the claims.

Figure 1, represents a view of portions of 30 an elevator wall or similar structure showing the improved sliding door operating device and lock applied to center opening sliding doors which are shown in closed position, portions of the sliding doors on the 35 next higher floor being also shown. Fig. 2, represents a similar view of parts of the same, the doors being shown in the open position.

Similar numbers of reference designate 40 corresponding parts in both figures.

As shown in the drawing *a* represents a wall having an opening *b* and furnished with the parallel guides *c* and *d* between which are slidable the doors *e* and *f*. On the 45 upper portion of the door *e* is secured the plate *5* which preferably extends upward and is furnished with the pivot *6* on which one end of the link *7* is pivoted, the other end of said link *7* being pivotally connected 50 with the upper end of the bent lever *8* which is mounted to swing on the pivot *9* secured

in the guide *c*, or similar fixed portion, and at its lower end *10* has the slot *11* free to slide and swing with respect to stud *12* secured to the door *f*.

55

The door *f* has the handle *13* and is preferably supplied with the latch *14* pivotally mounted on the said door and adapted to intercept the end *10* of the lever *8*, when the doors *e* and *f* are in the closed position, to 60 prevent the endwise movement of said lever in one direction whereby said lever *9* is locked against movement. The operation of latch *14* is facilitated and said latch is preferably sustained in the locking position 65 by the rod *15* connected with one end of said latch and slidable in guide eyes *16* and *17*, mounted on the door *f*, and having the thumb piece *18*.

In operating this improved sliding door 70 the thumb piece *18* is first pressed down to shift rod *15* and thus effect the swinging of latch *14* to the position shown in dotted lines in Fig. 1. Door *f* is now moved toward the right and, in such movement, stud *12* acts 75 on the edges of slot *11* to effect the swinging of lever *8*, the slotted end *10* thereof being free to slide on said stud *12*. Thus the upper end of lever *8* is caused to swing to the left and acting through the link *7* 80 and plate *5* effects the sliding of door *e* in the same direction therefore said doors *e* and *f* slide apart to present a center opening as shown in Fig. 2 of the drawings. The closing movement is of course the reverse of the opening movement and in such movement the end *10* of lever *8* finally 85 swings into line with latch *14* and is held by said latch against endwise opening movement.

90

Having thus described my invention I claim as new and desire to secure by Letters Patent.

1. The combination with a pair of sliding doors, a lever pivotally mounted on a fixed 95 pivot and having a slotted arm, a stud on one of said doors and engaged in said slot, and a link pivotally connected with said lever and the other of said doors, of a latch mounted on the first mentioned door and adapted to engage the end of said slotted arm.

100

2. The combination with a pair of sliding doors, a lever pivotally mounted on a fixed pivot, a stud on one of the doors engaging said lever and with respect to which said lever is free to slide and swing, and a link

5 pivotally connected with said lever and with the second of said doors, of a latch pivot-

ally mounted on the first mounted door in position to swing into engagement with said lever, and means for moving said latch.

AUGUST KRAUSE.
